UNITED STATES PATENT OFFICE.

GOTTLIEB H. SIMON, OF KIEL, WISCONSIN.

MILK-VAT.

SPECIFICATION forming part of Letters Patent No. 757,569, dated April 19, 1904.

Application filed April 1, 1903. Serial No. 150,530. (No model.)

To all whom it may concern:

Be it known that I, GOTTLIEB H. SIMON, a citizen of the United States, residing at Kiel, county of Manitowoc, and State of Wisconsin, have invented new and useful Improvements in Milk-Vats, of which the following is a specification.

My invention relates to improvements in sheet-metal vats for heating milk in the process of making cheese; and it pertains more especially, first, to the construction of the seams, by which they perform the twofold function of holding the separate sheets of metal together and as strengthening-flanges to prevent the bottom of the vat from bending or buckling by pressure or weight; second, to the construction of the vat at the converging ends of the seams of the bottom whereby the same is permitted to yield slightly without breaking; third, to the construction and arrangement of the strengthening-flanges and stay-bars upon the sides of the seams, which coöperate with the seams to stiffen the walls of the vat; fourth, to the construction and arrangement of the vertical sides of the vat; fifth, to the construction and arrangement of the strengthening-bands and bridge-blocks, which bridge-blocks are located at the junction of said bands with the longitudinal seams, and, sixth, to the manner of supporting the intermediate strengthening-bars between the sides of the bottom and the central longitudinal seam of the vat.

The construction of my invention is further explained by reference to the accompanying drawings, in which—

Figure 1 represents a side view. Fig. 2 is a longitudinal section. Fig. 3 is a bottom view. Fig. 4 is a transverse section drawn on line xx of Fig. 1. Fig. 5 is a detail in section drawn on line xx of Fig. 3, and Fig. 6 is a detail drawn on line yy of Fig. 3.

Like parts are identified by the same reference-letters throughout the several views.

My invention comprises two vats—an exterior vat A for the reception of hot water, which may be heated by steam-coils or in any other convenient manner, and the interior vat B for the reception of the milk. The inter-

rior vat B is suspended from the upper edges 50 of the vat A by horizontal flanges C. The respective vats are composed of a plurality of sections or separate sheets of metal D, which are connected together by longitudinal seams E and transverse seams F. The seams E and 55 F are formed by bending the contiguous edges of the several sections at right angles to their surfaces, forming downwardly-projecting flanges G G, which are soldered or otherwise secured together, and owing to the depth or 60 width of said bends they serve to strengthen the walls of the vats and prevent them from buckling or bending, as they would otherwise do if seamed together in the ordinary manner. It will be understood that when the milk has 65 been withdrawn from the inner vat B and the same is surrounded by water in the vat A the buoyancy of the water in the exterior vat (which is equal to its weight) is such as to press upwardly against the bottom of the interior vat 70 with great force, whereby it becomes necessary to provide the vat with rigid strengthening flanges or seams to prevent the same from being sprung inwardly when relieved of its contents, while the pressure and weight of the 75 water within the exterior vat has a tendency to spring the bottom of the same outwardly and downwardly, and it also becomes equally important to strengthen said exterior vat to resist the outward and downward pressure from 80 within. In view of the excessive pressure to which the vat is subjected I have provided the several seams at the junction of the sections with additional strengthening bars or flanges H, which are bolted or otherwise secured to the 85 respective sides of the flanges or angular bends G G, as indicated in Fig. 6. As the exterior vat A is not subjected to moisture, I preferably form the strengthening bars or flanges H of wood and secure them to the flanges G 90 by bolts I I and angular plates J J, as indicated in Fig. 6. As the wooden bars would be objectionable on the inner vat B, which is submerged in water, I preferably employ flat bars of metal K K upon the respective sides 95 of the flanges or seams G G, as indicated in Fig. 3. In addition to the seams and downwardly-projecting flanges located at the junc-

tion of the sections of metal comprising the bottom and sides of the vat I preferably employ one or more transverse reinforcing-bands L L, which are secured at their respective 5 upper ends to the side rails M M of the exterior vat, while their central portion extends downwardly and beneath the bottom of the vat, as indicated in Fig. 3. The bands L L are preferably made of angle-iron to give them 10 additional strength, and they are reinforced at their centers by bridge-blocks O and angle-irons P P, the bridge-blocks O and angle-irons P P being secured thereto by bolts Q Q, as shown in Fig. 5. Heretofore it has been common 15 to join the converging ends of the seams and strengthening-flanges at the center of the bottom of the inner vat, owing to which construction experience has demonstrated that such strengthening-flanges were liable to be broken at such point by the upward external 20 pressure of the water in the exterior vat. I have demonstrated by experience that the strength and durability of the vat is increased by removing a portion of the converging ends 25 of the seams and strengthening-flanges E and F of the center of the vat, as indicated at R, when I reinforce the center of the bottom at such point by the disk or metal plate S, which is secured to the bottom of the vat by a plurality 30 of rivets T. The bottom of the respective vats are preferably made V-shaped in cross-section, converging downwardly from their sides to their centers, as shown in Fig. 4, and the exterior vat is provided with supporting-legs V and transverse supporting 35 blocks or bearings U. The blocks or transverse bearings U are secured to the legs by bolts or rods W.

A' represents a reinforcing-bar which is located 40 between the longitudinal seam and the sides of the bottom and is held in place by and beneath the transverse strengthening-bands L L and serves to support the bottom of the vat. B' is a rectangular frame, preferably 45 formed of wood, which is secured to the upper edge of the vat and serves to retain the same in its proper rectangular shape.

I am aware that the longitudinal contiguous edges of cylindrical vessels—such as tubing, 50 oil-tanks, &c.—have heretofore been bent outwardly at right angles to the cylindrical portions of the vessel and secured together by bolts for the purpose of forming the joints between such longitudinal edges; but such angular flanges have not, so far as I have knowledge, heretofore been used for strengthening-flanges for open-mouthed vessels, milk-vats, &c.

Having thus described my invention, what 60 I claim as new, and desire to secure by Letters Patent, is—

1. An open-mouthed vessel such as a milk-vat comprising a plurality of sections of sheet

metal having their contiguous edges bent outwardly at right angles to their central portions and secured together so as to perform the twofold function of seams and strengthening-flanges in combination with parallel reinforcing-bars rigidly affixed to, and in direct contact with the sides of said strengthening-flanges, substantially as set forth. 65 70

2. A milk-vat comprising a plurality of sections of sheet metal, having their contiguous edges bent outwardly at right angles to their central portions and secured together, forming 75 seams and strengthening-flanges in combination with one or more transversely-arranged reinforcing-bands located between their respective ends and the center of the vat, secured at their respective upper ends to the side rails of the vat, and having their central portions extending downwardly and beneath the bottom of the vat, substantially as set forth. 80

3. A milk-vat comprising a plurality of sections of sheet metal, having their contiguous edges bent outwardly at right angles to their central portions and secured together, forming 85 seams and strengthening-flanges in combination with one or more transversely-arranged reinforcing-bands located between their respective ends and the center of the vat, and reinforcing bridge-blocks O, and angle-irons P, P secured to the center of said reinforcing-bands at their junction with the longitudinal 90 seams or strengthening-flanges of the sheet-metal section comprising the bottom of the vat, substantially as set forth. 95

4. A milk-vat comprising a plurality of sections of sheet metal, the contiguous edges of which are secured together by right-angular bends adapted to serve the twofold functions of seams and strengthening-flanges in combination with longitudinal reinforcing-rails H and angle-irons J, J, secured to the longitudinal 100 central flange of the vat by a plurality of bolts, substantially as set forth. 105

5. A milk-vat comprising a plurality of separate sections of sheet metal, secured together at their contiguous edges by right-angular bends forming seams and strengthening-flanges which are arranged both longitudinally and transversely of the vat and converge toward the center of the bottom, from the ends and sides of the vat, terminating at slight distances apart in combination with a separate plate of metal centrally located beneath the converging ends of said strengthening-flanges and secured to the bottom of the vat by a plurality of rivets, 110 substantially as, and for the purpose specified. 115

6. A milk-vat comprising a plurality of sections of sheet metal, having their contiguous edges bent outwardly at right angles to their central portions and secured together so as to 120 perform the twofold functions of seams and

strengthening flanges for the exterior surface of the vat arranged both longitudinally and transversely of the vat; a rectangular frame secured to the upper marginal edge of 5 the vat, and a plurality of vat-supporting legs secured at their upper ends to the sides of the vat, substantially as set forth.

In testimony whereof I affix my signature in the presence of two witnesses.
